FUEL INJECTION DEVICE

Robert Huber, Paris, France, assignor of nine-tenths to Raul Pateras Pescara, Paris, France, and one-tenth to Societe d'Etudes et de Participations, Eau, Gaz, Electricite, Energie, S. A., Geneva, Switzerland, a society of Switzerland

Application October 2, 1946, Serial No. 700,767
In France October 22, 1945

4 Claims. (Cl. 103—37)

1

The present invention relates to fuel injection devices of the accumulation type, that is to say fuel injection devices including means forming a fuel accumulator chamber fed by means of a pump, and a control member interposed between this chamber and the injector for placing them in communication with each other at the desired time. The invention is more particularly, although not exclusively concerned, among these injection devices, with those used for injecting fuel into the cylinder of an internal combustion engine.

The object of my invention is to provide a device of this type which is better adapted to meet the requirements of practice than those used for the same purpose up to the present time.

Preferred embodiments of my invention will be hereinafter described with reference to the accompanying drawings, given merely by way of example, and in which:

Fig. 1 is an axial sectional view of a fuel injection device made according to a first embodiment of my invention;

Fig. 2 is a similar view of a device of the same kind made according to another embodiment.

In the following description, it will be supposed that the invention is applied to the case of a fuel injection device for an internal combustion engine, for instance an engine belonging to a free piston machine.

The injection pump may be of any suitable construction. For instance, according to a conventional arrangement, it includes a piston 1 adapted to be rotated about its axis for adjustment of the amount of fuel fed on every stroke, this piston being provided with a cam-like surface 2 serving to determine, according to the angular position of piston 1 about its axis, either the end (Fig. 1) or the beginning (Fig. 2) of the fuel delivery by opening or closing, respectively, the communication between the inside of the pump cylinder 3 and the inlet port 4 of this cylinder.

The axial reciprocating movement of piston is ensured through any suitable means, for instance a cam (not shown by the drawings).

Means are provided for forming, for instance immediately above cylinder head 5, an accumulator chamber 6 adapted to coact with an accumulator piston 7 movable inside a sleeve 8 in line with accumulator chamber 6. This piston 7 is subjected to the action of a suitable force, for instance that exerted by a spring 7a which urges said piston toward the inside of chamber 6 so as to tend to reduce the volume thereof.

2

The communication between cylinder 3 and accumulator chamber 6 is controlled, in the embodiment of Fig. 1, by a valve 9 subjected to the action of spring 9a, or otherwise, as in the case of the embodiment of Fig. 2, by the action of special means which will be hereinafter described.

In order to prevent the possibility of too high pressures being developed in chamber 6, I may fit the latter with a safety valve such as 10 which opens, against the action of a spring 11, when the pressure in chamber 6 exceeds a predetermined value.

The means for controlling the communication between accumulator chamber 6 and conduit 12, which leads to the fuel injector, include a valve which, according to my invention, is operative in response to movements of piston 1, so as to open, in particular, when this piston is close to the end of its inward stroke.

For this purpose, I may either cause piston 1, or a part movable therewith, to act directly on said communication controlling valve, or have this valve operated by the pressure of a fluid subjected to the action of said piston or said part movable therewith, this fluid preferably consisting of the fuel delivered by the piston.

Fig. 1 shows an example of the first of these embodiments. The communication controlling valve in question, shown at 13 and subjected to the action of a spring 13a that urges it toward its closed position, has a stem provided with a groove 14 located opposite the inlet of a passage 15 in communication with conduit 12. This stem of valve 13 extends downwardly so as to project into cylinder 3. Thus, piston 1, at the end of its inward stroke, comes into contact with the end of said valve stem and pushes it so as to lift valve 13 from its seat. Accumulator chamber 6 is then brought into communication with conduit 12 through groove 14 and passage 15. A portion of the fuel present in chamber 6 and subjected to the pressure of accumulator piston 7 is injected into the engine cylinder by the injector fed through conduit 12.

Although valve 13 may be wholly independent of delivery valve 9, it is particularly advantageous to dispose valve 9 in an axial conduit 16 extending throughout valve 13.

In the embodiment of Fig. 2, the communication between accumulator chamber 6 and conduit 12 is also controlled by a valve 13' the stem of which is provided with a groove 14'. As in the above described embodiment the end of this valve 55 stem projects into cylinder 3 and valve 13' is

provided with an axial conduit 16'. But this last mentioned conduit is free from any closing means such as the delivery valve 9 of the preceding embodiment. On the other end the lower end of the stem of valve 13' is bevelled so that the end face of piston 1, when applied against this valve stem end, closes conduit 16' in a fluidtight manner.

In the embodiment of Fig. 2, the end of the delivery stroke must not vary. It takes place when the groove 18 of piston 1, which is constantly in communication with the inside of cylinder 3 through passage 19, comes opposite inlet port 4, whereas, owing to the provision of cam-like surface 2, the beginning of the delivery is variable, since delivery begins only when the edge 2 of piston 1 completely closes inlet port 4. Furthermore, the distance *a* between the end face of piston 1 and the lower end of the stem of valve 13' when the piston is at the end of its outward stroke, must be smaller than the distance *b* between the upper edge of groove 18 and the lower edge of port 14 for the same position of the piston.

The device shown by Fig. 2 works in the following manner:

After inlet port 4 has been closed by piston 1, the latter delivers fuel into accumulator chamber 6, this fuel being at a pressure corresponding to the strength of the spring 7a that acts on piston 1. During the beginning of this delivery stroke, valve 13' remains closed. However, when the end face of piston 1 gets close to the end of the stem of said valve, the liquid present in the annular space *c* of cylinder 3, i. e. between the lower end of said valve stem and the inner cylindrical wall of said cylinder, is subjected, due to the throttling of the communication between said annular space and conduit 16', to a pressure higher than that existing in chamber 6. This pressure difference causes valve 13' to lift from its seat without any metallic contact having taken place between the end face of piston 1 and the end of the valve stem. The layer of liquid present between these two parts thus plays a shock absorbing action which preserves valve 13' against premature wear and tear. This pressure increase in annular space *c* ceases when the upper edge of groove 18 reaches the lower end of port 4 and the bevelled edge 17 of the valve stem then comes into contact with the end face of piston 1 to close conduit 16 and present the fuel present in chamber 6 from flowing back into pump cylinder 3. However, the small movement necessary for applying the bevelled edge 17 of the valve stem against the end face of piston 1 is not sufficient for closing valve 13'. On the contrary, the latter remains open until piston 1 is on its return stroke.

According to another feature of my invention, instead of causing spring 7a to act directly upon piston 1, this spring is adapted to act upon an intermediate piece, for instance a piston 20 as shown in the embodiment of Fig. 1 or a cap 21 as shown in the embodiment of Fig. 2, this piece being in contact with the head 7' of accumulator piston 7, which is applied against said piece by the pressure existing in accumulator chamber 6. When the pressure in this chamber is low, spring 7a applies intermediate piece 20 or 21 against a fixed abutment. In the embodiment of Fig. 1, this abutment is for instance constituted by the upper part 22 of the pump body. In the embodiment of Fig. 2, it is constituted by an annular part 23 bearing on said pump body. Anyway, a certain play is left between the upper end of sleeve 8 and the head 7' of piston 7, so as to prevent

piston 7 from being injured by shocks of said head 7' against sleeve 8.

According to still another feature of my invention, the action of spring 7a is completed or even replaced by that of a compressed air cushion formed in the chamber 24 that contains this spring. For this purpose, this chamber is fitted with an inlet conduit 25 for the feed of this compressed air (see Fig. 1), this conduit being preferably provided with a check valve 26. The compressed air cushion in chamber 24 permits of reducing the strength of spring 7a and also of easily varying the pressure in accumulator chamber 6 and consequently the injection pressure.

A conduit 27 is provided for evacuating air or fuel leaks.

The fuel injection device according to my invention has the advantage of being particularly simple and of occupying the minimum volume.

While I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. A fuel injection device which comprises, in combination, means forming an accumulator chamber for fuel under pressure, a piston pump for feeding fuel to said chamber, a delivery conduit for leading fuel from said chamber to a fuel injector, a valve adapted to control communication between said chamber and said conduit slideable in line with the pump piston and adapted to be pushed by it into opened position at the end of the inward stroke of said piston, and a check valve between said chamber and said pump.

2. A fuel injection device which comprises, in combination, means forming an accumulator chamber for fuel under pressure, a piston pump for feeding fuel to said chamber, a delivery conduit for leading fuel from said chamber to a fuel injector, a valve adapted to control communication between said chamber and said conduit slideable in line with the pump piston and adapted to be pushed by it into opened position at the end of the inward stroke of said piston, and a check valve between said chamber and said pump mounted coaxially inside said communication controlling valve.

3. A fuel injection device which comprises, in combination, means forming an accumulator chamber for fuel under pressure, a pump for feeding fuel to said chamber including a cylinder and a piston movable in said cylinder, means forming a passage coaxial with and of smaller diameter than said cylinder extending between said cylinder and said chamber, a delivery conduit for leading fuel from said chamber to a fuel injector, and a valve adapted to control communication between said chamber and said conduit including a tubular stem slideable in said passage and extending into said cylinder, the end of said stem located in said cylinder having a beveled edge, said valve stem being so dimensioned as to come into contact with said piston at the end of the inward stroke thereof.

4. A fuel injection device which comprises, in combination, means forming an accumulator chamber, an accumulator piston slideable in a portion of said chamber, elastic means for urging

said piston in a direction tending to reduce the volume of said chamber, abutment means for limiting the movement of said piston in this direction, abutment means for stopping the action of said elastic means before said first mentioned abutment means are in action, a piston pump for feeding fuel to said chamber, a delivery conduit for leading fuel from said chamber to a fuel injector, and means operative by the pump piston for intermittently connecting said chamber with 10 said conduit.
